METAL AWNING

Filed Feb. 26, 1927

Patented Nov. 8, 1927.

1,648,334

UNITED STATES PATENT OFFICE.

HARRY D. CLOUD AND CLIFFORD BITTERMAN, OF LEXINGTON, KENTUCKY.

METAL AWNING.

Application filed February 28, 1927. Serial No. 171,186.

This invention relates to a metal awning for windows or the like, which may be simply and inexpensively stamped out of sheet metal and may be placed in position in any desired window opening and remain there indefinitely. When not in use, the sections of the awning may be drawn into collapsed position and held there until next desired for use. This application is an improvement on our prior Patent No. 1,615,214, granted January 25, 1927. It has for its purpose the provision of certain improvements in the patented construction which render it more efficient and satisfactory.

15 In the drawings:

Figure 1 is a section through the awning in its expanded position.

Figure 2 is a side view of one side of the awning.

20 Figure 3 is a section on the line 3—3 of Figure 1.

Figure 4 is a perspective of the fixed section of the awning.

25 Figure 5 is a perspective view of the first movable section which is pivoted to the fixed section.

There is illustrated in the drawings a common window casing A but it is understood that the awning may be applied to windows, doors, transoms or similar openings of various types.

30 The first section 1 is illustrated in Figure 4 and has two sides of substantially triangular form with a connecting top which may be slightly curved in either direction or substantially plane. The rear margin of the sides and top of this section have a flange 2 at substantially right angles thereto which is attached to the window casing A by 35 screws or similar fastening devices 3 which pass through openings 4 in the flange. The front edge of the top of this section is provided with a downturned flange 5.

35 The second section 6 has the form illustrated in Figure 5 and has a top and two sides, the latter being substantially triangular, but provided at their lower extremities with extensions 9 which lie in the same plane as the sides of the section but are bent 40 in this plane at such angle to the sides that when the section is in open position as shown in Figure 1, the rear edge of the extension 9 will lie against the flange 2 of the first section. These extensions 9 are provided with a series of pivot openings 10, 11, 45 12 and 13 which lie in a substantially ver-

tical line when the section is in open position. Pivots 14 pass through the openings 10 of the section 6 and into openings 14' of section 1, thus pivotally mounting the second section for movement to and from its open position. It will be noted that the section 6 is pivotally supported entirely by the first section. This pivot may, however, be extended into the window casing as in the case of our prior patent.

A third section 15 has sides of triangular form, but it does not have any extensions corresponding to the extension 9 of the second section. This third section is mounted 50 by pivots 16 which pass into the second section 6. In the form illustrated, there is shown also another intermediate section 17 of form similar to the section 15 and pivoted on pivots 18 which pass through the openings 12 in the section 6.

The outer section 19 is pivoted on pivots 20 which pass through the openings 13 of the section 6. This outer section lies in a substantially horizontal plane when the awning is open and the base thereof is adapted to abut against the flange 2 of the first section when in open position similarly to the engagement of the extensions 9 of section 2 with said flange. This flange 2 of the first section is broad enough to provide for such engagement although the section 19 has its sides located somewhat within the sides of the section 6.

Each section excepting the outer, is provided on its inner face near the back thereof with a wedge 22 as in our prior patent, with which contacts the sides of the next adjacent section when the device is moved to its closed position. Each section except the outer is provided on its inner face near the forward edge thereof, with a small roller 23 with which contacts the outer faces of the sides of the adjacent section. These rollers not only facilitate movement to and from open position, but provide points of constant engagement so that the sections are held against any lateral play which might cause rattling.

The provision of the flanges 9 on the section 6 and the corresponding portions of the outer section give a firm engagement of the base of these sections with the flange 2 of the fixed section when the device is in open position and thus greatly strengthens the whole construction. It is to be noted that the second section 6 is pivoted to the first

section, but that each of the succeeding sections is pivoted to the second section at points lying in a straight line, including the pivot of the second section to the first. This 5 provides a very compact and simple arrangement and the awning as constructed is readily moved to and from open position, but is held firmly against accidental or rattling movement between its various sections. It 10 is also obvious that the awning as a whole may be assembled and adjusted in the desired position by merely inserting the screws 3 or similar fastening devices.

The means for moving the awning to 15 closed position may be that illustrated in our prior patent or any other suitable means. It is obvious that minor details of construction and the precise form and configuration of the sections may be changed without de- 20 parting from the spirit of the invention which is to be regarded as limited only by the scope of the appended claims.

We claim as our invention:

1. A metal awning comprising a section 25 adapted to be rigidly supported and having an inwardly extending flange around its rear margin, a second section pivotally carried by the first and having its sides terminating in extensions at an angle thereto which engage 30 the flange when the second section is in open position, and a plurality of additional sections each pivoted to the second section.

2. A metal awning comprising a section 35 adapted to be rigidly supported and having an inwardly extending flange around its rear margin, a second section pivotally carried by the first and having its sides terminating in extensions at an angle thereto which engage 40 the flange when the second section is in open position, and a plurality of additional sections each pivoted to the second section at points below the pivot of the second section to the first.

3. A metal awning comprising a section

adapted to be rigidly supported and having 45 an inwardly extending flange around its rear margin, a second section pivotally carried by the first and having its sides terminating in extensions at an angle thereto which engage 50 the flange when the second section is in open position, and a plurality of additional sections each pivoted to the second section at points below the pivot of the second section to the first.

4. A metal awning comprising a section 55 adapted to be rigidly supported and having an inwardly extending flange around its rear margin a second section pivotally carried by the first and having its sides terminating in extensions at an angle thereto which engage 60 the flange when the second section is in open position, and a plurality of additional sections each pivoted to the second section, the outer section also provided with an inner end which engages the flange when the awning is 65 in open position.

5. A metal awning comprising a section 70 adapted to be rigidly supported and having an inwardly extending flange around its rear margin, and a second section pivotally mounted within the first and having its sides terminating in extensions at an angle thereto which engage the flange when the second section is in open position.

6. A metal awning comprising a section 75 adapted to be rigidly supported, a second section pivotally carried thereby, a plurality of additional sections each independently pivoted to the second section, and rollers on the inner face of each section which engage 80 the outer face of the sides of the adjacent section to facilitate movement of the pivoted sections and hold the parts firmly against relative lateral movement.

In testimony whereof, we have hereunto 85 subscribed our names.

HARRY D. CLOUD.
CLIFFORD BITTERMAN.
